UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF PHILADELPHIA, PENNSYLVANIA, COPARTNERS TRADING AS JOHN BROMLEY & SONS.

DESIGN FOR A RUG.

SPECIFICATION forming part of Design No. 36,033, dated August 26, 1902.

Application filed July 31, 1902. Serial No. 117,901. Term of patent 3½ years.

To all whom it may concern:

Be it known that I, ADOLPH PETZOLD, a citizen of the United States, residing in the city of Philadelphia, State of Pennsylvania, have invented and produced a certain new, original, and ornamental Design for a Rug, of which the following is a full, clear, and exact description, reference being had to the accompanying drawing, forming a part of this specification.

My invention relates to the surface ornamentation of woven rugs; and it consists of the novel and ornamental design for a surface pattern therefor shown in the accompanying drawing, in which is illustrated a rectangular rug design, the essential and distinguishing characteristics of which are the solid-ground border *a*, whose inner edges, formed by straight

lines *b*, inclose an open center. A bouquet of flowers *c* occupies the immediate center of this open central field and trailing stems and leaves *d* the remainder of the field-center. Other and connected stems and leaves *e* partly cover the solid border edge *a* and overlap the field-center and also extend over the inner border-lines *b* at each corner.

I claim as new and of my invention—

The ornamental design for a rug, substantially as shown and described.

In testimony whereof I have hereunto affixed my signature this 2d day of July, A. D. 1902.

ADOLPH PETZOLD.
